ATTACHMENT FOR PRESSES

Norman F. Carden, Jr., Durham, N. C.

Application January 10, 1947, Serial No. 721,408

2 Claims. (Cl. 271—63)

1

This invention relates to the paper ejecting mechanisms of presses and more particularly to an attachment for applying an adjustable pressure to the material ejecting rollers of a conventional "Multilith" press.

Printing machines of the type mentioned are usually provided with a driven paper ejecting roll and the printed sheets are held against the surface of the ejecting roll by means of pivotally supported rollers which bear by gravity against the upper surface of the paper sheets. Where the rollers bear against the surface of the paper by their weight only, the ejection of printed sheet material from the press is often impositive and irregular, particularly where there may be variation in the weight and texture of the paper used.

It is an object of this invention to provide an attachment for printing machines which will exert an adjustable pressure for urging rollers against the surface of paper on a driven ejecting roll.

It is another object of this invention to provide an attachment easily applied to "Multilith" presses for assuring proper action of the paper ejecting mechanism.

It is still another object of this invention to provide an attachment for the roller supports of paper ejecting mechanisms which applies an adjustable spring pressure effective to urge the rollers to firmly hold paper in contact with a driven ejector roll.

Other objects and advantages of this invention will become readily apparent from the following detailed description of the preferred embodiment of the invention shown in the accompanying drawing, wherein,

Figure 1 is a perspective view of the paper ejecting portion of a "Multilith" press machine having pressure attachments applied to the roller supports thereof.

Figure 2 is an enlarged perspective view of a portion of the apparatus shown in Figure 1.

Figure 3 is an elevation view of the attachment shown in Figures 1 and 2 removed from the printing machine.

Referring to the drawings, which for the purposes of illustration show a preferred embodiment of the invention, portions of the side plate members of a conventional "Multilith" press are designated by the numerals 10 and 11. The side plate members are connected by a rigid horizontal tie bar 12. The ejector roll 13 is journaled in the side plates 10 and 11 and is provided with a driving gear, not shown, for positively rotating the roll. A bar 14 extends between the side plates

2

10 and 11 and is provided with paper strippers 15 for removing the printed sheets from the impression cylinder 16.

Conventional structure for holding the printed sheet material against the driven ejector roll 13 includes a pair of rollers 17 supported above the roll. The rollers 17 are journaled at the outer ends of the side arms 18, the inner ends of the side arms being slidably mounted on the cross shaft 19. The cross shaft 19 may be supported for limited movement toward and away from the blanket cylinder 16 on arms 20, the latter being pivotally supported on the inner side of each side plate 10 and 11. Tension spring 21 may be provided between the outer end of the arm 20 and a stud on the side plate 11 to bias the cross shaft 19 toward the cylinder 16. The inner ends of the side arms 18 are pivotally supported on the shaft 19 and may be moved laterally therewith to position the rollers 17 a proper distance apart for the width of paper being printed and ejected by the machine. Each support for an ejecting roller 17 is formed by a pair of spaced parallel side arms 18 connected together by a nut and bolt 22 extending between the arms and located intermediate of the ends of the arms. A roller 23 may be journaled between the inner ends of the arms 18 to bear against the impression cylinder 16.

The roller support attachment of this invention includes a member 30 having a bushing 31 at its inner end adapted to be secured between the pair of side arms 18 by means of the nut and bolt 22 extending therethrough. The outer portion 32 of the member 30 is bent upwards at an angle to the inner portion and is provided at its outer end with an upstanding boss 33 engaged by the coil spring 34. The outer portion 32 of the member 30 is also provided with laterally projecting lugs 35 for engagement with the upper edges of the side arms 18. A clamping member 36 is adjustably secured to the horizontal tie bar 12 by means of a wing bolt 37, and is provided with a downwardly extending threaded stud 38 secured to the bottom of the clamping member. An adjusting nut 39 is threaded on the stud 38 and provided with a downwardly extending boss 40 engaged by the upper end of the coil spring 34. The nut 39 may be provided with a knurled edge 41 to facilitate turning the same in adjusting the distance of the boss 40 from the clamping member 36, thereby permitting easy adjustment of the pressure exerted by the spring 34 on the roller support.

The attachment described above is easily ap-

plied to existing machines of the "Multilith" type by removing the usual spacing collar on nut and bolt 22 between the side arms 18, and substituting therefor the bushing 31 of the member 30. The projecting lugs 35 engage the upper edges of the side arms 18 to prevent the outer portion 32 of member 30 from engaging the ejector roller 17. The roller and side arm assembly is positioned laterally along the cross shaft 19 so that the roller 17 is properly spaced for the width of the paper to be ejected. Next the clamp 36 is secured to the tie bar 12 by wing bolt 37 in a position above the roller 17. The spring 34 is positioned between the boss 33 of member 30 and the boss 40 of adjusting nut 39, and manual adjustment of the nut 39 along the stud 38 away or toward the clamp 36 serves to increase or decrease the spring pressure applied to the roller support side arms 18 through the lugs 35.

It will be readily apparent that the simple attachment described above may be easily and quickly applied to the paper ejecting mechanism of existing or new machines of the type illustrated, and that the attachment provides means for applying an adjustable spring pressure tending to urge the paper ejecting rollers against the surface of paper or sheet material, whereby the latter is held in contact with a driven ejector roll and evenly ejected from the machine. The attachment also permits the rollers to be positioned laterally as desired for the width of paper to be ejected. It has been found that use of a device of the character described is effective to assure proper and uniform ejection of printed sheets from printing presses, and that it avoids delays due to jamming or uneven action of conventional ejection mechanisms.

Although the above description relates to a specific form of a device for attachment to a "Multilith" press, it will be readily apparent that many changes in minor details, proportions and design may be made in applying the device to similar machines and presses, and still be within the scope of this invention as defined in the following claims.

What I claim is:

1. An attachment for the paper ejecting mechanism of a lithographing machine of the type

having a driven ejector roll and a roller cooperating therewith supported by a pivotally mounted arm, said attachment comprising an elongated member, one end of said member being adapted to be pivotally connected to said arm remote from said roller, the other end of said member being adjacent to said roller and having means engaging said arm, a clamp adapted to be secured to said lithographing machine adjacent to said roller, resilient means positioned between said clamp and the end of said member adjacent to said roller, and adjustable means engaging said resilient means for varying the compression of said resilient means.

2. An attachment for the paper ejecting mechanism of a lithographing machine of the type having a driven ejector roll and a roller cooperating therewith supported between a pair of pivotally mounted arms, said attachment comprising an elongated member, one end of said member being adapted to extend between said arms and having a bushing thereon adapted to be pivotally connected to said arms intermediate of the ends of one of said arms, the other end of said member being adjacent to said roller and having projecting lugs for engagement with said arms adjacent to said roller, a clamp adapted to be secured to said lithographing machine adjacent to said roller, a coil spring positioned between said clamp and the end of said member adjacent to said roller, and threaded means carried by said clamp engaging one end of said coil spring for adjusting the compression force of said spring applied to said member.
